STAPLING HAMMER

Norris R. Libert, Chicago, Ill., assignor to Stapling Engineers, Inc., Chicago, Ill., a corporation of Illinois

Application June 6, 1945, Serial No. 597,750

6 Claims. (Cl. 1-49)

1

This invention relates to an improved stapling hammer.

The primary object of the invention is to provide a stapling device to be operated after the manner of a hammer adapted to drive an individual staple with each blow struck upon the object or material to be stapled.

A further object is to provide a stapling hammer of this type in which a supply of staples are carried in a magazine and which, upon striking the surface into which the staple is to be driven, operates to automatically feed a staple from the magazine into position and drive it all in the striking or driving operation.

A further object is to provide a stapling hammer of this type in which the power from the blow to feed and drive the staple is transmitted through a toggle mechanism which acts as a positive driving connection between the hammer head and the staple.

A further object is to provide a device of this character which is rugged in construction and relatively inexpensive to manufacture.

My invention resides in the construction, combination, and arrangement of the parts, herein-after described, in connection with the accompanying drawings which illustrate one embodiment of the invention, and set forth in the appended claims.

Referring to the accompanying drawings,

Fig. 1 is a view in side elevation of a stapling hammer embodying the invention, a portion of the outer end of the handle being broken away to show the interior thereof;

Fig. 2 is a vertical longitudinal section of the structure shown in Fig. 1, this view being taken on the line 2-2 of Fig. 5;

Fig. 3 is a detail end view of the upper portion of the hammer head section of the device;

Fig. 4 is a detail end view of the lower portion of the hammer head section;

Fig. 5 is a plan view of the hammer head section and a portion of the handle section of the structure shown in Fig. 1;

Fig. 6 is a perspective view of the lower portion of the striking plunger guide;

Fig. 7 is a side elevation of the hammer head section with a portion of the magazine section being in section and with the staple driving parts being shown in intermediate driving position;

Fig. 8 is a view similar to Fig. 7 showing the staple driving parts in fully completed driving position;

Fig. 9 is an enlarged detail section on the line 9-9 of Fig. 7; and

Fig. 10 is a detail transverse section on the line 10-10 of Fig. 7.

The device shown in the drawings comprises in general the hammer head section A and a magazine and handle section B. The staples C (Figs. 7, 8, and 9) for which the present device is adapted are U-shaped in section having legs

5 or prongs C¹ which are driven into the material to be stapled and which are connected by a cross member C². These staples, while made as individual pieces, are assembled together side by side and bound by some binder such as cement to form a long, channel-like strip which can be handled as a unit and which is adapted to be placed in the magazine of the device and fed endwise to the driving mechanism.

10 The handle section and hammer head section of the device are built upon a frame which in the present structure is made of a single piece of metal which is formed U-shaped or channel-shaped in section and L-shaped in profile. The handle section B of this frame has upright parallel walls B¹ and a connecting bottom wall B². The channel is open at its top throughout its length so that the strips of staples may be inserted into position to be fed to the hammer head section. At one end, the walls B¹ have vertical extensions B³ which form the short leg of the L and provide a mounting for the operating parts of the hammer head section.

15 Within the handle section is a staple guiding member D which extends the length of the handle and is channel or U-shaped in section like the frame member B. This guide member has vertical walls D¹ connected by a bottom wall D² which is fastened by welding or otherwise to the bottom wall of the frame member to hold the guide in position. The walls D¹ of the guide, as shown more clearly in Fig. 9, are spaced from the walls B¹ of the frame to provide room for the prongs of the staples.

20 25 30 35 The strip of staples is placed in inverted position in the magazine so that the cross-connecting member C² of the staples ride or slide along the upper edges of the guide member walls D¹ so that the strip of staples can be fed to the throat in 40 the hammer head section.

35 40 45 50 55 60 The strip of staples is fed to the hammer head section by a pusher or feeder member E which is in the form of an inverted or channel-shaped member slidable along the upper edges of the staple guide and having its legs E¹ positioned in the spaces between the guide member walls D¹ and the frame walls B¹ in the same manner that the strip of staples is positioned. The end of this pusher or feeder member bears against the outer end of the strip of staples and is yieldingly acted upon to feed the strip by the coil spring 1 which at its outer end 2 is anchored to the outer end of the frame. The spring extends along the bottom portion of the staple guide D to the head section where it is brought around an idler pulley 3 and its end 4 fastened to the feeder member so that the pull of the spring on the feeder will be in the direction to feed the strip of staples to the hammer head section. The idler pulley 3 is rotatable on a shaft 3¹ secured in the upright walls of a U-shaped support 5 which is positioned within the guide member D and secured to the

walls of said guide member by welding or otherwise.

The top of the handle section of the frame is enclosed by a cover plate 5 which forms part of the grip of the handle but which is slidable lengthwise on the upper edges of the frame member so that the magazine may be opened to permit the insertion of the strip of staples. This cover plate is held in place on the handle section of the frame by a U-shaped band member 6, the walls of which conform to and around the exterior of the frame B and secured by suitable means to the edges of the cover plate. The cover plate 5, on its under side, carries a strip 7 which yieldingly bears upon the top surface of the strip of staples for the purpose of confining the staples to prevent any possibility of the strip buckling while under the pressure of the spring-actuated feeder member. At its inner end, this strip has a shoulder 8 formed to engage a lug 9 on the feeder member so that when the cover strip is slid lengthwise to open the magazine the feeder will be retracted to permit the insertion of a strip of staples. This connection 8 and 9 between the cover and the feeder member also serves as a stop when the strip of staples is within a few staples of being exhausted and thus prevents the feeder member from entering the discharge throat of the device.

Within the hammer head section is a guard member F which is positioned above the strip of staples. This guard member F consists of a plate with an upturned end F¹ located at the end of the magazine section and forming a guide for the driving member. The plate F is placed above the strip or row of staples but close enough thereto to confine the staples in the channel and prevent possible buckling or displacement of the staples out of alignment. The plate has two upstanding extensions or walls F² which are secured to the inner faces of the frame wall extensions B³ by welding or otherwise to hold the plate F in position.

The head has a guide member G for the striking plunger H which is U-shaped in cross-section and comprises the cross wall G¹ and the side walls or legs G². This guide member embraces the end of the hammer head section of the frame and its walls are positioned parallel with said frame walls and against the exterior thereof. The cross wall G¹ is spaced from the end of the walls B¹ of the frame sufficiently to provide a guiding space for the striking plunger H to permit said guiding plunger to move vertically or longitudinally of itself. The walls G² of the guide have three sets of extensions. The upper extensions G³ are pivotally mounted on the walls B¹ of the frame by means of a bolt 10 having a head at one end and a nut threaded thereon at the other end. This bolt extends through the frame walls B³ and the extensions G³ from one side of the structure to the other.

The horizontal extensions G⁴ of the guide member have the bolt 11 extending therethrough and through the walls G² of the frame for the purpose of holding the guide member G in place for normal operation. In the event that the staples become jammed in the throat, the bolt 11 can be removed and the guide member swung outwardly on the upper pivot bolt 10 and away from the end of the head so as to permit access to the throat.

The lower extensions G⁵ reach downwardly to the striking face J of the hammer head section (Figs. 4 and 6) and have inturned flanges G⁶

which overlie the walls B¹ of the hammer head section and are spaced from the ends of said walls to form the discharge throat K for the staples. This throat, as shown more particularly in Figs. 2, 7, and 8, is just sufficient for a single staple, and as the strip of staples is fed to the throat, the lugs or flanges G⁶ serve as stops to prevent more than a single staple being fed beyond the end of the magazine walls B¹. The flanges G⁶ also serve 10 as a guide for the lower portion of the striking plunger H.

The striking plunger H is in the form of a rectangular bar vertically movable in the guide G and arranged with its lower end extending beyond or below the striking face J of the head section so that when the operator swings the head section toward the object, the plunger will contact the object first and be moved upwardly in its guide until its lower end is substantially flush 15 with the striking face J of the head. At its lower end, the plunger has two wings H¹ which overlie the outer face of the walls B¹ of the magazine section to force or compress the layers of material to be stapled close together in an area surrounding the staple while the staple is being driven. The upper end of the striking plunger has lateral shoulders H² which engage the upper edges G⁷ of the guide member and provide limit 20 stops for the downward movement of the striking plunger.

The movement of the striking plunger in an upward direction when the blow is struck upon the object is transmitted to the staple driving member L through the medium of a toggle mechanism 25 which is located in the upper portion of the head section between the two wall extensions B³ and which includes a rocker lever M. The staple driving member L is a flat, hardened plate or strip of the proper width and thickness to fit the throat K of the head section. At its upper end portion this driving member has two lateral wings L¹ which lie against the inner faces of the walls B³ of the frame and thereby form guides to keep the driving member in its vertical line of movement. 30 These wings also carry a bolt member 12 which extends through the wings and projects on either side thereof. These projecting ends of the bolt ride in vertically disposed elongated slots L² in the walls B³ of the frame and guide the movement of the driving member and maintain the driving member in the vertical plane of its movement.

The rocker lever M is in fact comprised of two parallel pieces pivotally mounted upon the pivot bolt 10 between the upper portions of the walls B³ of the head section, but since both of these pieces are alike in construction and function alike, they are referred to herein as a rocker lever. The arms M¹ of this rocker bear against the upper rounded end H³ of the striking plunger. The other arms M² of this lever form a part of the toggle mechanism. The other part of the toggle mechanism is comprised of two links M³ which are pivotally connected by means of the pivot bolt 55 M⁴ to the arms M², and by the bolt 12 to the driving member L.

Thus when the striking plunger is moved upwardly in the head by the force of the blow, it 60 rocks the rocker lever M about its pivot and, through the toggle mechanism, power is transmitted to the driving member L to move this member in a direction reverse to that of the striking plunger; that is, the driving member L is moved downwardly in the throat and ejects the 65 staple from the throat and projects it beyond

the striking face J so that it will be driven into the object, this position of the parts being shown in Fig. 8.

As soon as the blow has been struck upon the object and the staple driven therein, and the hammer lifted away for the next driving operation, the driving member L is retracted to its normal position by means of a spring 13 which is anchored at one end 14 to the guide member G and extends over the pivot bolt 10 and its other end 15 anchored to the driving member L. This spring thus retracts the driving member L and through the toggle mechanism and rocker M restores the striking plunger to its projected position in advance of the striking face J. The driving or lower end of the driving member L is retracted to a position just above the strip of staples in the magazine; and during the retraction, as the end passes the strip, the strip is fed forward to position the next staple in the throat.

It will be noted that the toggle mechanism and rocker lever provide a positive driving connection between the striking plunger and the driving member without lost motion. These parts can be so proportioned that the relative length of movement of the striking plunger and the driving member can be arranged as desired, that is, the striking plunger can be arranged to move a greater distance than the driving member and thus increase the driving power of the driving member.

I claim:

1. In a stapling hammer of the class described, the combination of a hammer head section having a striking face, a magazine handle section terminating in a discharge throat in said head, means in the magazine section for feeding staples successively to said throat, a driving member movable in said throat to eject a staple from the throat and beyond the striking face of said head, a rocker lever in the head, a link connected with said lever and said driving member and forming therewith a toggle, and a striking plunger positioned to contact the object in advance of the striking face of the head for actuating said rocker lever.

2. In a stapling hammer of the class described, the combination of a handle section forming a magazine in which a strip of staples is moved to successively position the individual staples in discharge position and the head section having a discharge throat opening through the striking face of the head section, a staple driving member movable in said head to eject the end staple of the strip through the throat beyond the striking face and into the object, a striking plunger vertically movable in the head in parallel relation to the movement of the driving member and having the end projecting beyond the striking face of the head to contact the object in advance of said striking face, a rocker lever in said head to be actuated by the striking plunger, and means connecting the rocker member with the driving member to actuate the driving member.

3. In a stapling hammer of the class described, the combination of a handle section forming a magazine in which a strip of staples is moved to successively position the individual staples in discharge position and the head section having a discharge throat opening through the striking face of the head section, a staple driving member movable in said head to eject the end staple of the strip through the throat beyond the striking face and into the object, a striking plunger vertically movable in the head in parallel relation to the

movement of the driving member and having the end projecting beyond the striking face of the head to contact the object in advance of said striking face, a rocker lever in said head to be actuated by the striking plunger, means connecting the rocker member with the driving member to actuate the driving member, and means to retract the driving member and restore the striking plunger to normal position after each operation.

5. In a stapling hammer of the class described, the combination of a frame channel-shaped in cross-section and having an elongated portion forming a magazine section terminating at one end in a discharge throat, means within the frame for feeding a series of staples successively to said discharge throat, an ejector and driving blade movable in said throat to project the end staple of said series beyond said frame and into the object, parallel wall extensions of said frame forming a head section, a striking plunger, a U-shaped guide member for said plunger mounted on said extensions, a rocker lever pivotally mounted between said extensions adapted to be actuated by said striking plunger, and link members connecting the rocker lever with the driving member for actuating said driving member.

10. In a stapling hammer of the class described, the combination of a frame channel-shaped in cross-section and having an elongated portion forming a magazine section terminating at one end in a discharge throat, means within the frame for feeding a series of staples successively to said discharge throat, an ejector and driving blade movable in said throat to project the end staple of said series beyond said frame and into the object, parallel wall extensions of said frame forming a head section, a striking plunger, a U-shaped guide member for said plunger mounted on said extensions, a rocker lever pivotally mounted between said extensions adapted to be actuated by said striking plunger, and link members connecting the rocker lever with the driving member for actuating said driving member.

15. In a stapling hammer of the class described, the combination of a hammer head section having a striking face and having a throat opening in said face through which the staples are ejected, a driving member in said head movable in said throat to eject a staple therefrom and projecting it beyond the striking face, a striking plunger movable in said head in reverse direction to that

20. of the driving member and positioned to contact the object in advance of the striking face of the head, a rocker lever in said head adapted to be actuated by the plunger, and toggle means connected with said rocker member and said driving member for actuating the driving member in a direction reverse to that of the striking plunger.

25. In a stapling hammer of the class described, the combination of a hammer head section having a striking face and having a throat opening in said face through which the staples are ejected, a driving member in said head movable in said throat to eject a staple therefrom and projecting it beyond the striking face, a striking plunger movable in said head in reverse direction to that

30. of the driving member and positioned to contact the object in advance of the striking face of the head, a rocker lever in said head adapted to be actuated by the plunger, and toggle means connected with said rocker member and said driving member for actuating the driving member in a direction reverse to that of the striking plunger.

35. In a stapling hammer of the class described, the combination of a hammer head section having a striking face and having a throat opening in said face through which the staples are ejected, a driving member in said head movable in said throat to eject a staple therefrom and projecting it beyond the striking face, a striking plunger movable in said head in reverse direction to that

40. of the driving member and positioned to contact the object in advance of the striking face of the head, a rocker lever in said head adapted to be actuated by the plunger, and toggle means connected with said rocker member and said driving member for actuating the driving member in a direction reverse to that of the striking plunger.

45. In a stapling hammer of the class described, the combination of a hammer head section having a striking face and having a throat opening in said face through which the staples are ejected, a driving member in said head movable in said throat to eject a staple therefrom and projecting it beyond the striking face, a striking plunger movable in said head in reverse direction to that

50. of the driving member and positioned to contact the object in advance of the striking face of the head, a rocker lever in said head adapted to be actuated by the plunger, and toggle means connected with said rocker member and said driving member for actuating the driving member in a direction reverse to that of the striking plunger, a handle member for said hammer head, and means within the handle for feeding staples successively to said discharge throat.
